HOLDER FOR KITCHEN TOOLS OR THE LIKE

Harold Charles Dowit, 11835 Sheldon St.,
Sun Valley, Calif.

Filed Mar. 9, 1965, Ser. No. 84,161

Term of patent 14 years

(Cl. D44—29)

The essential features of my new design are shown in full lines on the drawing.

I claim:

The ornamental design for a holder for kitchen tools or the like, as shown and described.
